UNITED STATES PATENT OFFICE.

MONTAGUE H. ROBERTS, OF ENGLEWOOD, NEW JERSEY, ASSIGNOR TO FRANKLIN RAILWAY SUPPLY COMPANY, OF NEW YORK, N. Y., A CORPORATION OF DELAWARE.

LOCOMOTIVE-BOOSTER LUBRICATION.

Application filed June 22, 1923. Serial No. 647,009.

My invention relates to locomotive booster lubrication, my object being to provide effective and reliable lubrication for the various parts of such boosters that need to be lubricated, preferably by means quite automatic in its action. In the embodiment of the invention hereinafter described, which is the best known to me, I accomplish this through splash action substantially throughout. Various advantages realizable through the invention will appear from the description.

In the drawings, Fig. 1 is a plan view of a locomotive booster conveniently embodying my invention, with half of the cover and various other parts broken away, and with the engine cylinder and steam admission structure in midsection.

Figs. 2, 3 and 4 show vertical fore and aft sections, taken as indicated by the correspondingly numbered lines in Fig. 1.

Fig. 5 shows a transverse section through the engine frame and casing structure, taken as indicated by the line 5—5 in Fig. 2, certain upper portions being broken away.

Fig. 6 is an edge view of one part of the cover of said casing, from the right of Fig. 1.

In general design and operation, as well as in various features and details of construction, the horizontal booster here shown closely corresponds to the disclosures of applications for United States patent by Ingersoll, Serial No. 417,215, filed October 15, 1920; by Peters, Serial No. 591,687, filed October 2, 1922, and Serial No. 592,003, filed October 3, 1922; and by myself jointly with Peters, Serial No. 624,207, filed March 10, 1923; all assigned to the assignee of this application.

It comprises (see Fig. 1) a couple of horizontal reciprocating steam engines disconnectably driving a locomotive axle 10. In general, the booster serves to increase the tractive power of the locomotive (especially in starting and at low speeds), by making drivers of wheels which would otherwise merely help to sustain the deadweight and perhaps improve the riding qualities of the locomotive. In practice, means are provided whereby the booster can be connected or disconnected by the engineer at will, and also means for automatically disconnecting it when the speed of the locomotive exceeds a predetermined value. When it is disconnected in either way, its steam supply is like-

wise cut off, so that it cannot race or consume steam uselessly. Such means need not be here illustrated or described, however, since their specific construction and operation form no part of my present invention. 60

At the forward end, the booster frame and casing structure 11 is mounted about the axle 10, and supported thereby; at the rear end, it may be supported from a suitable part such as the main locomotive frame, or a 65 trailer truck to which the axle 10 belongs, in any suitable manner (not shown).

(Figs. 1 to 3). The booster engines are arranged one at either side of the structure 11, with a common transverse crank shaft 70 12 adjacent and paralleling the axle 10, and with their cylinder and steam admission and exhaust structure 13 at the other end of said structure 11. As here shown, the cylinders 14 and the valve chests 15 are substantially 75 isolated from the machinery space in the interior of the structure 11, in order to obviate leakage of steam or water or condensation into the latter. For this same purpose, the valve stem stuffing boxes 16 are provided 80 with a pipe connection 17 for draining off water of condensation through the bottom of the casing 11 at 18. At either side, the end walls 19 of the machinery space adjoining the cylinders 14 are spaced some inches 85 from the cylinder heads. In the present instance, the cylinder and valve chest structure 13 is cast separate from the rest of the structure 11 and secured to the mid portion of its corresponding end wall, against which 90 it directly abuts.

As shown in Figs. 1 to 5, the forward portion 20 of the structure 11 overlies the axle 10 and affords bearings 21 resting on it to support this end of said structure. The 95 bearings 22 for the crank shaft 12 are on fore and aft flanges or webs 23 upstanding from the bottom of the structure 11, and serving as strength elements of said structure. The gearing 24 for interconnecting 100 and disconnecting the shafts 10 and 12 is located between the pairs of bearings 21 and 22, and the overhung engine cranks 25 and connecting rods 26 are at either side, in the lateral compartments or "wells" between the members 23 and the booster casing sides 27. A transverse upstanding flange or web 28 connects the members 23 and thus coacts with them to form a central compartment or well for the gearing 24 and its actuating 110

means 29. As shown in Figs. 1 and 4, the gearing 24 includes a gear 30 fast on the axle 10, a gear 31 fast on the crank shaft 12, and an idler gear 32 mounted on a double rocker frame 33 pivoted to the structure 11 at 34. The idler 32 is continually in mesh with the crank shaft gear 31, and is thrown into or out of mesh with the axle gear 30 when the actuating means 29 swings the rocker 33 up or down. The piston rods 35 extend through the casing walls 19 into the lateral compartments of the machinery space (above mentioned), and the guides 36 for the cross heads 37 are on the bottom of said compartments. The crank pins 38 carry return crank eccentrics 39 that actuate the engine valves 40 through rods 41, bell cranks 42, and links 43 connecting the latter to the valve stems 44. The bell cranks 42 have their bearings in brackets 45 secured to the fore and aft members 23. In the present instance, the bottom and the parts 19, 21, 22, 23 and 28 of the booster frame and casing structure 11 form a unitary bed plate casting, while the sides 27, brackets 45, top plates 47 and 48, and various other parts are separate.

This description of the booster mechanism and structure will render the more detailed description of its other lubricating features and provisions readily intelligible.

Generally speaking, the lubrication of the gearing 24 and the associated parts 29, 35, etc., is accomplished by the splash action of the gears on the oil in the central compartment above-mentioned and its forward extension 46 about the gear 30. Accordingly, the bottom of this gear case extension 46 slopes or curves fore and aft, both ways, to a low point under the gear 30 (Figs. 3 and 4), so that the oil may always drain back to the gear. Similarly, the lubrication of each engine is, in general, accomplished by the splash action of its moving parts (especially crank 25 and connecting rod 26) on the oil in the corresponding lateral compartment. As shown in Fig. 2, the bottom of each lateral compartment slopes fore and aft to a low point under the crank shaft 12, —a trough-like depression 49 between the cross head ways 36 assisting to drain the oil back into the path of the crank 25. The bearings 21 on the axle 10 are supplied with lubricant more or less by the splash action of both gearing and engines, as hereinafter described. As shown in Figs. 1, 2 and 5, the gearing and engine compartments communicate through openings 51 at several points, as well as over the tops of the members 23, to permit interchange of lubricant and to compensate for "cross splashing". In general, the lubricant is supplied to the low pressure regions, or areas, of the various journal or shaft bearings.

The action of gearing 24 and of parts 25

and 26 on the oil is to churn it up and splash it about in a fine spray or mist that fills the gearing and engine compartments and falls or settles on their walls and on all parts and surfaces within them, thus lubricating effectively such as are sufficiently exposed. Accordingly, the piston rods 35, the ways 36, and the cross heads 37 are amply lubricated in this manner. In order to insure ample lubrication of the crank pins 38 and the wrist pins 52, their bearings in the ends of the connecting rods 26 are pierced with radial holes 53, 54 to admit the oil to the bearing surfaces at the regions of lower pressure. In addition, each connecting rod 26 has in its upper side a longitudinal groove 55 extending from one of the oil holes 53 at the crank pin 38 to the oil hole 54 at the wrist pin 52, to collect oil and feed it to the bearings; and each connecting rod 26 also carries a scoop 56 over the lowermost of the crank pin oil holes 53, to collect the oil and force it into the bearing as the scoop traverses the pool of oil in the bottom of the casing 11. To insure ample lubrication at the crank shaft bearings 22, their caps have cup recesses 57 in their upper sides and are provided with oil holes 58 to admit and distribute oil through circumferential grooves 59 in the lower pressure regions of the bronze or other bearing surfaces. Over each cup 57 the cover plate 48 has a cup-like depression 60, that serves to collect the oil splashed up on the cover and insure its dripping into the cup. To assure proper lubrication of bell cranks 42, valve stems 44, and associated parts, the bearing brackets 45 are provided with semi-circular open-topped catch basins or troughs 61 to collect the oil splash. Oil thus collected works out through the bearings at the ends of each trough 61, runs down the bell crank arms, and lubricates the pivotal connections of the members 41 and 43. From the middle of each trough 61, also, oil is led off through a pipe 62 that extends through the corresponding member 23 and discharges the oil on the upper side of the valve stem 44, just adjacent its stuffing box 16.

I have already referred to the fact that (instead of being lubricated like truck axle bearings) the bearings 21 on the axle 10 in the structure 20 are in the present instance supplied with lubricant from the interior of the structure 11, by splash action. For this purpose, oil pockets 64, open overhead to catch the splash from gearing and cranks, may be cast on the inside of the front wall of the casing 11, about in line with members 23, and provided with holes or ducts 65 leading to the lower pressure regions of the bearing surfaces. From the bottom of each bearing, there is an opening 67 into the subjacent hollow lower portion or pocket 66 of the corresponding axle bearing box. In

practice, this pocket 66 may contain waste in contact with the under side of the axle 10, to absorb oil running down around the axle from the catch pocket 64 and distribute it 5 thoroughly over the entire axle surface. Each pocket 66 has a return opening 68 through the rear casing wall into the corresponding lateral compartment of the casing, and a clean-out opening with pivoted 10 cover 69. The opening 68 assures the maintenance of an adequate predetermined oil level in the waste pocket 66, yet prevents accumulation to the point of running over at 15 69. The pockets 66 may conveniently be cast integral with the lower portion of the gear case 46, and secured to the rest of the structure 11.

The oil supply in the casing 11 can be introduced and replenished through an opening with removable cover 70 in one of the 20 side plates 27. A pet-cock 71 at the front of the structure 11, outside its portion 66, affords a convenient indication of when the oil reaches the proper level in the casing 11. 25 At the low point of the transverse oil well or trough below the crank shaft 12 a draw-off opening with a screw plug 73 (Figs. 2 to 4) may be provided for each lateral compartment of the casing 11. As shown in 30 Fig. 2, this plug 73 has a central opening 74 from its top down, and a radial hole 75 drilled in from its side. By partially unscrewing this plug 73, any water that finds its way into the casing 11 can be regulably 35 drawn off without risk of discharging any substantial amount of oil.

What I claim is:

1. A booster comprising a closed casing structure mounted about a railway vehicle 40 axle at one end, engine cylinder and motive fluid admission means at the other end, splash lubricated engine mechanism in the casing, and means for inter-connecting and disconnecting the axle and said mechanism 45 also splash lubricated.

2. An enclosed substantially horizontal booster mounted about and disconnectibly driving a railway vehicle axle, and substantially self-lubricating by splash action of 50 its engine mechanism and disconnectible gearing on a common body of lubricant.

3. A locomotive booster comprising a substantially horizontal closed engine frame and casing structure mounted about a railway 55 vehicle axle at one end, with engine cylinder and motive fluid admission means at its other end substantially isolated from the interior of the casing to obviate leakage of motive fluid into the latter; and mechanism 60 in said casing substantially self-lubricating by splash action, said mechanism including crank shaft and operating connections thereto from the engine pistons, valve gearing, and gearing for operatively interconnecting 65 and disconnecting crank shaft and axle.

4. A booster comprising a substantially horizontal closed engine frame and casing structure mounted about a railway vehicle axle at one end, with engine cylinder and motive fluid admission structure at its other 70 end; substantially self-lubricating engine mechanism in said casing, including crank shaft and means of connection between the same and the moving engine parts in said cylinder and admission structure; and gearing in said casing for operatively interconnecting and disconnecting crank shaft and axle, said gearing being also substantially self-lubricating. 75

5. A booster comprising a closed engine 80 frame and casing structure mounted about a railway vehicle axle at one end, with engine cylinder and motive fluid admission means at its other end substantially isolated from the interior of the casing, means dividing the interior of the casing into engine 85 and gearing compartments, a horizontal engine in said engine compartment substantially self lubricating by splash action, and gearing in said gearing compartment for operatively interconnecting and disconnecting engine and axle also self-lubricating by splash action. 90

6. A splash lubricated booster for driving a railway vehicle axle comprising horizontal 95 engines with common crank shaft, and gearing between them for operatively interconnecting and disconnecting crank shaft and axle; an engine frame and casing structure enclosing engines and gearing, including 100 strength elements upstanding from the casing bottom around said gearing; the separate wells for engines and gearing thus formed intercommunicating to permit interchange of lubricant. 105

7. An enclosed booster journaled about and disconnectibly driving a railway vehicle axle, said booster being substantially self-lubricating and also supplying lubricant to its journal bearing at said axle. 110

8. A booster comprising a substantially horizontal closed engine frame and casing structure, with a railway vehicle axle at one end an engine cylinder and motive fluid admission structure at its other end; and a crank shaft journaled in said casing paralleling said axle, means of connection between said crank shaft and the moving parts in said cylinder and admission structure, gearing for operatively interconnecting and disconnecting crank shaft and axle, and journal bearings for said casing structure at the axle, all automatically lubricated through splash action of parts on said crank shaft. 115

9. A splash lubricated booster comprising a substantially horizontal closed engine frame and casing structure mounted about a railway vehicle axle, with fore and aft strength elements upstanding from the casing bottom; a transverse crank shaft jour- 120
130

naled in bearings at said fore and aft members and geared to said axle between them, with cranks overhung in the lateral compartments formed by them; piston rod cross heads and connecting rods extending between the same and said cranks in said compartments; valve gearing including valve stems at the inner sides of said fore and aft members; and means for collecting the engine splash in said compartments and supplying the same to lubricate crank shaft bearings and valve stems.

10. A splash lubricated booster comprising a substantially horizontal closed engine frame and casing structure mounted about a railway vehicle axle; engines in said casing with cross head guides on the bottom thereof, connecting rods grooved on their upper sides to lubricate the crank pins and cross head pins, and valve gearing including rocker bearing supports affording catch reservoirs for supplying lubricant to the valve stems; and a common overhung crank shaft for said engines journaled in bearings 25 with oil intakes and disconnectibly geared to said axle between said bearings, with means above for collecting the oil splash and supplying it to said intakes.

11. A substantially horizontal enclosed booster disconnectibly driving a railway vehicle axle and substantially self-lubricating by splash action, with journal bearing means for said axle at one end of the enclosing casing of the booster communicating 30 therewith to receive lubrication from the

splash and permit return of lubricant to the casing.

12. A substantially horizontal enclosed booster disconnectibly driving a railway vehicle axle and substantially self-lubricating 40 by splash action, with journal bearing means for said axle at one end of the enclosing casing of the booster, and means open upward in the booster casing for collecting the splash therein and supplying the same to 45 said bearing:

13. A substantially horizontal enclosed booster disconnectibly driving a railway vehicle axle and substantially self-lubricating 50 by splash action, with journal bearing means for said axle at one end of the enclosing casing of the booster, a pocket adjacent said axle open to the same for lubrication of said bearing means by waste in said pocket and receiving an overhead supply of lubricant from the splash in said booster casing, and means for maintaining a predetermined lubricant level in the waste pocket.

14. An enclosed locomotive booster journaled on the axle which it drives, said booster being substantially self-lubricating 60 by splash action, and provided with means for supplying the splashed lubricant to the low pressure regions of said journal bearing.

In testimony whereof, I have hereunto signed my name.

MONTAGUE H. ROBERTS.

DISCLAIMER

1,600,427. — *Montague H. Roberts*, Englewood, N. J. LOCOMOTIVE-BOOSTER LUBRICATION. Patent dated September 21, 1926. Disclaimer filed October 23, 1934, by the assignee, *Franklin Railway Supply Company*.

Hereby enters this disclaimer to that part of the claims in said specification which is in the following words, to wit:

“7. An enclosed booster journaled about and disconnectibly driving a railway vehicle axle, said booster being substantially self-lubricating and also supplying lubricant to its journal bearing at said axle.

“8. A booster comprising a substantially horizontal closed engine frame and casing structure, with a railway vehicle axle at one end, an engine cylinder and motive fluid admission structure at its other end; and a crank shaft journaled in said casing parallel to said axle, means of connection between said crank shaft and the moving parts in said cylinder and admission structure, gearing for operatively interconnecting and disconnecting crank shaft and axle, and journal bearings for said casing structure at the axle, all automatically lubricated through splash action of parts on said crank shaft.”

“11. A substantially horizontal enclosed booster disconnectibly driving a railway vehicle axle and substantially self-lubricating by splash action, with journal bearing means for said axle at one end of the enclosing casing of the booster communicating therewith to receive lubrication from the splash and permit return of lubricant to the casing.

“12. A substantially horizontal enclosed booster disconnectibly driving a railway vehicle axle and substantially self-lubricating by splash action, with journal bearing means for said axle at one end of the enclosing casing of the booster, and means open upward in the booster casing for collecting the splash therein and supplying the same to said bearing.”

“14. An enclosed locomotive booster journaled on the axle which it drives, said booster being substantially self-lubricating by splash action, and provided with means for supplying the splashed lubricant to the low pressure regions of said journal bearing.”
